UNITED STATES PATENT OFFICE.

GEORGE C. TERWILLIGER, OF WAYNE, NEBRASKA.

DESIGN FOR A FORGE-CHIMNEY.

SPECIFICATION forming part of Design No. 34,584, dated May 28, 1901.

Application filed April 26, 1901. Serial No. 57,634. Term of patent 7 years.

To all whom it may concern:

Be it known that I, GEORGE C. TERWILLIGER, a citizen of the United States, residing at Wayne, in the county of Wayne and State of Nebraska, have invented and produced a new and original Design for Forge-Chimneys, of which the following is a specification, reference being had to the accompanying drawings, forming a part thereof.

10 Figure 1 is an elevation of a forge-chimney embodying my new design. Figs. 2 and 3 are respectively side and plan views of the same.

As shown in the accompanying drawings, the leading or material feature of my design 15 consists of a lower rectangular portion A, provided with a forward triangular extension or hood B, having a bead B' at its edge and feet or lugs a a a a at its lower four corners, and an upper pyramidal portion C, the contour of which gradually changes from rectangular at the bottom, as at c', to cylindrical at the top, as at c².

Having fully described my design, what I claim as new, and desire to secure by Letters Patent, is—

The design for a forge-chimney as herein shown and described.

In testimony whereof I have signed my name to this specification in the presence of two subscribing witnesses.

GEO. C. TERWILLIGER.
